COIN CONTROLLED MOVIE-SOUND
MACHINE

John F. Eakins, Evanston, Ill., assignor, by mesne assignments, to Phonovision Corporation, Chicago, Ill., a corporation of Illinois

Application September 29, 1942, Serial No. 460,086

1 Claim. (Cl. 194—12)

This invention relates to coin controlled movie-sound machines of the type in which the customer inserts a coin or coins, putting the machine into operation to show to the patron a movie and at the same time to reproduce a recording of associated and usually synchronized music or other sound reproduction.

Prior machines of this general type have the disadvantage that they are non-selective. Usually the various film episodes are arranged in series on a continuous film. When a coin is inserted by a patron, one episode is reproduced and the insertion of the next coin effects the reproduction of the next episode on the film. Consequently, the patron must take the next episode which is coming up on the film and he has no control over what particular artist he will see and hear.

As is well known, public fancy runs to hit tunes and to particular orchestras and no one is able to determine in advance what particular tunes will catch on with the public. Neither can anyone foretell how long a hit tune will endure in the public fancy. The fact that in prior machines the odds are many times against a customer obtaining for his coin a selection which he really wants is a serious commercial disadvantage in machines of this type.

One of the principal objects of the present invention is to provide a relatively simple machine of this type arranged so that the patron can determine exactly which of a plurality of visual and associated sound recordings he is to hear for his coin.

A further object of the invention is to provide a machine of this type in which a patron can insert a plurality of coins, or coins of different denomination, and become enabled to select a corresponding number of recordings, which recordings are then reproduced for him one after another.

Other objects, advantages and capabilities of the invention will appear from the following description of a preferred embodiment thereof taken in conjunction with the accompanying drawings, in which:

Figure 1 is a vertical sectional view showing the combined movie-sound machine located inside a cabinet;

Fig. 2 is a wiring diagram of the electrical connections thereof;

Fig. 3 is a fragmentary detail showing the sliding structure and the frames or slides for selec-

tively positioning the films with respect to their light sources;

Fig. 4 is a detail showing one of the selector pins and associated mechanism;

Fig. 5 is a diagrammatic view showing the general arrangement of the sound film and associated parts;

Fig. 6 is a fragmentary front view of the picture film; and

Fig. 7 is a similar view of the sound track film.

For the purposes of my invention, I prefer to provide a plurality of film episodes on a relatively large film 10 which in the specific embodiment shown is arranged for ten episodes. The film 10 is wide enough for ten frames 11 and each episode consists of one longitudinal series of frames. The frames may be about a third of an inch wide and in view of the relatively large size of film necessary, I prefer to provide at least one additional row of sprocket holes 12 in addition to the sprocket holes 13 along the edge of the film.

The mechanism is contained within a cabinet 14 which is provided with a transparent screen 15 suitably of frosted glass upon which the picture is projected. Light from the lantern 16 is projected through a frame of the film 10 onto a mirror 17 from whence it is reflected upon a mirror 18 from which in turn it is again reflected onto the screen. A suitable lens structure 19 is provided on the outer side of the film 10 from the lantern 16 whereby the image is focused upon the screen 15.

The film 10 is continuous, its ends being cemented together so as to constitute a relatively large loop. The excess film may be stored in any suitable manner. For example, it may be arranged on sprocket wheels 20 located behind the lantern 16 so that the major part of the film is located in vertical lengths in the manner shown in the drawings.

The film is fed from the sprockets 20 by means of feed sprockets 21 and cooperating rollers 22 through a frame 23 which is movably located between the lantern 16 and the lens structure 19 so that any particular row of frames of the film may be brought into alignment with the light emitting opening 24 of the lantern 16. The lantern 16 is provided with a rotatable shutter 25 whereby the light is interrupted in necessary manner for movie reproduction.

The sound tracks for the several film episodes of the film 10 are preferably recorded on a film

26 which is mounted on sprockets 27 which are preferably in alignment with the sprockets 20 and are rigidly connected thereto so that the sprockets 27 and 20 rotate in unison.

The film 26 passes through a guide 28 which is rigidly connected to the guide 23 so that it is movable therewith in the horizontal direction to bring the sound track 29 corresponding to the series of frames in alignment with the light gate 24 of the lantern 16 into alignment with a lantern 30 and photocell pickup 31. The photocell pickup 31 is connected to an amplifier 32 which reproduces the recording on the track on the loud speaker 33 mounted in the wall of the cabinet. The sound track film 26 is drawn through the gate 28 at uniform speed by means of a lower sprocket wheel 34 and complementary roller 35.

An upper sprocket wheel 34, together with a complementary roller 35, supplies the film from the sprockets 27 to the gate 28. The sprockets 34 are in alignment with and are rigidly secured to the sprockets 21. The sprockets 21 and 34, together with their complementary rollers, are carried by bearings on the structure 58 which carries the two frames 23 and 28.

The sprockets 20, 21, 27 and 34 are driven continuously in appropriate directions by a motor 36 through a suitable gear reduction 37. The motor 36 is preferably a synchronous motor so that the pitch of the music is preserved. The lower sprockets 21 and 34 are driven by a shaft 38. The shaft 38 carries a worm 39 which meshes with a worm gear 40 rigidly mounted on the shaft carrying the lower sprockets 21 and 34.

Also mounted on the shaft 38 is a worm 41 which drives a worm gear 42 rigidly mounted on a shaft 43 which extends through a claw housing rigidly mounted on the structure 58 which carries the frames 23 and 28. The housing 44 carries three claws 45 which are arranged to enter the sprocket holes 12 and 13 and effect the normal step-by-step movement of the film in usual movie projector fashion. The housing 44 contains the necessary mechanism for driving the claws from the shaft 43. This mechanism may be of any known or suitable type and since many such mechanisms are in ordinary use in movie projectors, it is unnecessary to describe the same in detail.

The shaft 38 is driven by a worm 40 which meshes with a worm gear 41 which is carried by the structure 58. The worm gear 41 is slidably mounted on a gear shaft 42 which extends from the gear reduction housing 37. The arrangement is such that the worm gear 41 is free to slide along the length of the shaft 42 while it is driven thereby in all its positions.

The shafts carrying the upper sprockets 20 and the upper sprockets 27 are provided with gears 46 which are operatively connected by idler gears 47. The forward gear 46 is driven by a gear 48 which is rigidly connected to a worm gear 49. The worm gear 49 is driven by a worm 50 on a shaft 51 extending from the gear reduction 37.

The lower sprocket wheels 20 are provided with gear wheels 52. The two rearmost sprocket wheels 20 being driven in opposite directions, have their gear wheels 52 in mesh. The other lower sprockets 20 have their gear wheels 52 connected in series by immediate idler gears 53.

The lower series of sprockets 20 is driven by a gear 54 in mesh with the gear 52 of the foremost of the lower sprocket wheels 20. The gear 54 has rigidly secured thereto a worm gear 55

which is in mesh with a worm 56 on the lower projecting end of the shaft 51. Since all the lower sprocket wheels 20, with the exception of the last one, have to rotate in a direction opposite to that of the upper sprockets 20, one of the worms 50 and 56 is a right-hand worm and the other is a left-hand worm.

The shutter 25 is driven by suitable gearing 57 and a chain 123 which is driven directly from the shaft 51. The gear ratios are such that the shutter position is properly correlated to the claw mechanism. The film is sufficiently long to provide for suitable bights above and below the slide 28. Similar bights are provided for the film 26 above the gate 28 and below the sprocket wheel 34. It will of course be understood that the films are of the same length and that they are located with respect to the claw mechanism and with respect to the lower sprocket 34 to provide synchronization between the visible and audible reproductions and that all the sprocket wheels are driven at the same tooth speed.

The upper sprocket 21 may suitably be driven by means of a worm 124 on a shaft 125 carried by the structure 58. The shaft 125 carries a worm 126 which is in mesh with a worm gear 127 also carried by the structure 58.

The gear 127 is slidably mounted relative to a gear shaft 128 which carries a gear 129 which may mesh with a suitable gear, for example the gear 48, to provide the necessary drive for the upper sprocket wheel 21 notwithstanding that the position of this sprocket wheel may vary.

The slide frames 23 and 28 are mounted on the integral structure 58 adapted for slidable movement in the horizontal transverse direction, provision being made so that the pictures of every episode and every sound track can be brought into registry with their cooperating lanterns 16 and 30 for coordination of the film episodes with the corresponding sound recording.

The structure 58 is movable transversely by means of a rack 59 carried by the structure 58 which is in mesh with the pinion 60 driven at suitable speed by a reversible motor 61 through a gear reduction 62.

The rack 59 carries two projections 63 which are adapted to cooperate at the ends of their travel with a projection 64' of a reversing switch 64 which controls the direction of operation of the motor, power being supplied to the motor through this switch. The arrangement is such that when the motor is energized, the structure 58 travels to the left and then to the right until it is arrested by means which will now be described.

The pinion 60 is preferably of such size that it moves the structure 58 through its full travel by rotation slightly less than one revolution. From the pinion 60 extends rigidly a shaft 65 which carries at its end a conductive radial arm 66 which is insulated from the shaft. This arm is consequently arranged to perform oscillatory movements of somewhat less than 360° and it is arranged to engage any of a plurality of pins 67 which correspond in number to the number of selections, each pin corresponding to one individual selection. The pins 67 are arranged in arcuate pattern and lie in a direction parallel to the shaft 65. Selector means, which will hereinafter be described, are provided for projecting any desired one or more of the pins into the path of the arm 66 and automatic means are provided for returning the pins to their normal position after cooperation with the arm 66.

The machine being intended for coin operation, I provide in the cabinet means for receiving from patrons coins of various denominations. Thus, I provide a coin chute 68 which may be intended for the reception of a dime. A dime falling through this coin chute momentarily closes a switch 69 which is in circuit with an electromagnet 70 located adjacent a ratchet wheel 71. The armature 72 of the magnet 70 carries a dog 73 adapted to move the ratchet wheel 71 one tooth from its normal position. In this normal position, a pin 74 carried by the ratchet wheel holds open a switch 75 but when the ratchet wheel is moved one or more tooth spaces from its normal position, this switch becomes closed. A similar pin 76 on the other side of the ratchet wheel is arranged in the normal position of the ratchet wheel to open a switch 77 but when the ratchet wheel is moved one or more tooth spaces away from its normal position, the switch 77 is closed.

Of course other coin chutes may be provided for the reception of coins of other denominations. Thus, I may provide another coin chute 78 for the reception of a fifty-cent piece and in the fifty-cent piece coin chute I may provide five switches 79 all of which are connected to operate the magnet 70 so that the ratchet wheel 71 is displaced five tooth spaces by the insertion of a fifty-cent piece.

The magazine switch constituted by the ratchet wheel 71 and the switch 75 limits the number of selections which can be made, since, as hereinafter pointed out, selections can be made only when the switch 75 is closed and each selection effects return of the ratchet wheel 71 one tooth space towards its normal position.

Selections are made by a plurality of buttons 80 each of which corresponds to one particular selection. The buttons are pushed outwardly towards normal position by means of springs 81. Each button carries a bridging contact 82 which is normally located between a relatively large stationary contact 83 and a relatively small stationary contact 84. Adjacent contacts 83 and 84 are connected together by conductors 85 and one end of the series constituted by contacts 83, 82, 84 and conductor 85 is connected to one power line 36.

When a button 80 is pressed inwardly, the movable contact 82 clears the contact 84. Consequently, if the patron tries to press two buttons 80 simultaneously, separation of one pair of contacts 82 and 84 will prevent supply of energy to the stationary contact 83 associated with the other button. The contact 82 of the button 80 nearest the power line 86 connects the long contact 83 with a contact 87 so that the power line 86 is connected to the solenoid 88 which is individual to the controlling button 80 and is individual to the same selection.

The button 80 also carries a movable contact 89 which is adapted to establish a circuit between two associated contacts 90 and 91. It is arranged so that this last-named circuit is established not later than the instant the contact 82 engages the contact 87 since the establishment of this circuit discharges credit from the ratchet wheel 71. All the contacts 90 are connected to power line 86 and all the contacts 91 are connected to a common line 92 which is connected to an electromagnet 93 (similar to the electromagnet 70).

The other side of the electromagnet 93 is connected to one side of a magnet 95 which is in turn connected to the other power line 94 through 75

switch 75. The electromagnet 95 is similar to the electromagnet 70 but it is arranged so that it feeds the ratchet wheel 71 one tooth in the opposite direction, that is, towards its normal position, each time that the magnet 95 is energized. The electromagnet 93 is associated with a ratchet wheel 96 so that on each energization the ratchet wheel 96 is moved one step from its initial or normal position.

10 The ratchet wheel 96 carries a pin 97 which controls a switch 98. In the normal position of the ratchet wheel 96, this switch is open and in all other positions it is closed. The switch 98 is arranged in parallel with the switch 77, both being connected to the power line 86. The other sides of the switches 77 and 98 are connected to the amplifier 32, the lamps of the lanterns 30 and 16, and to a conductor 116 which supplies the motors 36 and 61. Consequently, these lamps 20 and the amplifier are energized at all times during which either of the ratchet wheels 71 or 96 is displaced from their normal position and one of the motors 36 and 61 is in operation at such times. When both ratchets are returned to their 25 normal position, the lamps and amplifier are disconnected from the power supply and both motors are stopped.

It is to be noted that when there is credit on the ratchet 71, selections can be made energizing 30 the appropriate solenoids 88 and each actuation of a button 80 to make such selections has the effect of moving the ratchet wheel 71 one step back towards its normal position and has the effect of moving the ratchet wheel 96 one step 35 away from its normal position, thus transferring the credit from the ratchet wheel 71 to the ratchet wheel 96.

The other sides of the solenoids 88 are connected to the side of the switch 75 adjacent the 40 magnet 91. The circuit through any of the solenoids 88 cannot be completed unless switch 75 is closed.

The main motor 36 is connected to the power line 94 and the selector motor 61 is likewise connected to the power line 94 through the reversing switch. The other terminal of the motor 36 is connected to a switch 101 on a lockup relay 102. The other terminal of the selector motor 61 is connected to a switch 103 also on the lockup relay 102. The other sides of the switches 101, 103 are connected to the conductor 116. The switches 101, 103 are correlated so that when one is open, the other is closed. Consequently, one of the motors 36, 61, operates at all times when either 50 of the switches 77 or 98 is closed and when the two ratchet wheels 71 and 96 are returned to the normal position the operation of both motors ceases.

The locking relay 102 comprises a main magnet 60 104 one side of which is connected to the power line 86. The other side of the winding 104 is connected to a contact 105 which bears against one of the films, preferably the film 26. On the other side of this film is a contact 107 which is 65 connected to the power line 94. The contacts 105, 107 are in alignment so that they make contact momentarily when an opening 108 provided in the film 26 comes into registry with them. This opening 108 and the contacts 105 and 107 are arranged so that this contact is made momentarily at the end of a reproduction. The opening 108 is sufficiently small that the contact is of short duration and the film 26 overruns the contacts 105 and 107 slightly so as to separate them almost 70 immediately. The energization of the main mag-

net 104 opens the switch 101, which is biased towards closing position, and closes switch 103. The lockup relay 102 is provided with a latch 109 which locks the switch 103 closed and the switch 101 open. To effect the unlocking of the relay 102, a magnet 110 is provided to cooperate with an armature which forms part of the latch 109. One side of the magnet 110 is connected to the power line 86. The other side of the electromagnet 110 is connected to one side of a plurality of solenoids 111.

The solenoids 111 are arranged in alignment with the solenoids 88 and a pin 67 is located with-in each set of aligned solenoids. The pin 67 comprises a main portion of ferrous material and a reduced projecting end 67' which may be of non-magnetic material such as brass. The aligned solenoids are provided with stop means so as to limit the movement of the pin 67 in both directions. The arrangement is such that when a solenoid 88 is energized, its pin 67 will be moved to one end of its path so that its non-magnetic end 67' projects into the path of the arm 66. When the corresponding solenoid 111 is energized, the pin 67 is retracted in opposite direction to its normal position.

The conductive arm 66 is connected to the power line 94 by means of a suitable brush 94'. Each pin 67 is electrically connected to the other side of its solenoid 111 by means of contact 111' (Fig. 4). It will readily be understood that when the arm 66 strikes a pin 67, a circuit is completed through its associated solenoid 111 and through the electromagnet 110 so that the relay 102 is unlatched, resulting in the opening of the switch 103 and the closing of the switch 101. This circuit is, of course, immediately broken by the withdrawal of the pin 67 from the arm 66.

The contact 105 is also connected to one side of an electromagnet 112 associated with the ratchet wheel 96 in the same manner as the electromagnet 85 is associated with the ratchet wheel 71. The other side of the electromagnet 112 is connected to the power line 86 and the arrangement is such that each time contacts 105 and 107 engage, that is, at the end of each reproduction, the ratchet wheel 96 is returned one step towards its initial position.

It is to be understood that the pins 67 are correlated to the arm 66 so that the arm 66 is adapted to engage a pin 67 each time that one row of the frames on the film 10 is in registry with the opening 24. The structure 58 is provided with a notched bar 113 which is provided with notches 114 having the same spacing as the rows of frames on the film 10. A spring pressed roller 115 is adapted to engage these notches in such manner as to hold this structure with a film frame in alignment with the opening 24. In the spacing of the pins 67 and the notches 114 provision is made for the unequal spacing due to the central sprocket holes 12.

The operation is as follows:

When the machine is out of operation, the opening 108 of the film 28 is just clear of the contacts 105, 107, the ratchets 71 and 96 are in the normal position, and the switches 75, 77 and 98 are open. No selection can be made at this time since switch 75 has opened the circuit of the solenoids 88. The machine cannot be energized until the ratchet wheel 71 has been moved from its normal position by the insertion of a coin or coins. If a dime is inserted in the coin chute 68, the electromagnet 70 is energized once and the ratchet wheel 71 is moved one tooth space from its normal position, thus closing the switches 75 and 77.

The closing of the switch 77 supplies current to the lamps, to the amplifier, and to the selector motor 61, the relay 102 having been locked up by the movement of the opening 108 past the contacts 105 and 107 at the end of the last operation.

The selector motor goes into operation, moving the structure 58 to the left and to the right through its complete travel, the reversal being effected by the actuations of the reversing switch 64 at the end of travel in each direction. If a button 80 is now pressed inwardly, a circuit is completed through magnets 93 and 95, the switch 75 being closed. The energization of the magnet 95 returns the wheel 71 to normal position, opening the switch 75 and opening the switch 77. The energization of the magnet 93 moves the ratchet wheel 96 one step from normal position, closing the switch 98 so that the supply of energy to the lamps, amplifier and motors is maintained. The motor 61 consequently remains in operation, moving the structure 58 to the left and to the right.

It has been noted that only one button 80 is operative at one time, since the movement of one button inwardly disconnects all contacts 83 of buttons more remote from the power line 86. Consequently, only that button which is pressed in at one time and which is nearest the power line 86, is effective. The contact 82 of this button connects the line 86 to its individual solenoid 88 and this solenoid is energized before the switch 75 opens.

The energization of the solenoid 88 projects its associated pin 67 into the path of the oscillating arm 66 and consequently it arrests this arm with the line of frames on the film 10 corresponding to this selection in alignment with the opening 24. Engagement of the arm 66 with the projected pin 67 establishes the circuit through the associated solenoid 111 and through the electromagnet 110 of the lockup relay 102. The switch 103 is consequently opened, with the result that the motor 61 stops and the switch 36 closes so that the motor 36 is put into operation its circuit being completed through the closed switch 98.

As a result of the opening of the switch 75 resulting from the actuation of the selector button 80, no further selections can be made until a further coin or coins is inserted in one of the coin chutes.

The motor 36 going into operation, projects the selected picture upon the screen and the movement of the sound track film effects the reproduction of the corresponding sound recording by the amplifier 32 and the loud speaker 33.

The electrical system remains in this condition until the end of the reproduction when the opening 108 establishes momentary engagement between the contacts 105 and 107. Such engagement establishes a circuit through the electromagnet 104, locking up the relay 102 and conditioning the switch 103 for the operation of the selector motor 61. The selector motor 61 does not go into operation because the circuit established between the contacts 105 and 107 energizes the electromagnet 112 and effects the return of the play control ratchet wheel 96 to its normal position, opening the switch 98 and breaking the supply circuits for the lamps, the amplifier and the motors.

If a plurality of coins, or a coin corresponding to a larger number of plays, is inserted in the coin chutes 68 and 78, the ratchet wheel 71 is moved a plurality of steps from its normal posi-

tion. In this case the switches 75 and 77 are closed, the selector motor 61 is put into operation, and current is supplied to the lamps and to the amplifier. If the patron makes a selection by pressing in a button 80, he puts the machine into reproduction as previously described.

In this case he can make a plurality of selections corresponding to the value of the coins inserted, each selection that he makes effecting the return movement of the ratchet wheel 71 one step towards its initial position. When he has made the corresponding number of selections, he has pushed out the corresponding pins 67 and he has moved the ratchet wheel 71 back to initial position and opened the switches 75 and 77 so that he can make no more selections.

The motors now remain in alternate operation continuously until all the selections corresponding to the projected pins 67 have been played. At the end of the first selection, contacts 105 and 107 engage with the result that the main motor 36 ceases to operate and the selector motor 61 is put into operation. Engagement between the contacts 105, 107 also takes one credit off the ratchet wheel 98, moving it one step towards its initial position. The switch 98 does not open until after the last selection paid for has been reproduced.

When a plurality of pins 67 have been projected, the oscillating arm 66 is moved by the motor 61 until it engages one of the projected pins 67. This projected pin arrests the arm 66 with the result that the corresponding recording is reproduced. This engagement effects the return of the engaged pin 67. When the selector motor 61 is again put into operation after the reproduction of the recording corresponding to the pin 67 which has just been referred to, the arm 67 again starts to move, engaging another pin, with the result that the corresponding recording is reproduced and that pin is returned to its normal position. This operation continues until all the pins 67 are returned to normal position and after the last reproduction is effected, electromagnets 112 and

104 are energized, opening the switch 98 and thereby terminating the operation of the machine, and conditioning the switch 103 for resumption of operation of the selector motor 61 after a further coin or coins has or have been inserted in the coin chutes.

Although my invention has been described in connection with specific details of a preferred embodiment thereof, it must be understood that such details are not intended to be limitative of the invention except in so far as set forth in the accompanying claim.

I claim:

15 In an automatic moving picture machine, a coin counter adapted to be actuated by the insertion of coins, a pair of switches controlled by said counter, selector means rendered operative by said counter, means including one of said switches controlling the operability of said selector means, a play counter, a switch in parallel with the other of said switches controlled by said play counter and arranged to supply energy to an amplifier, a projector lamp, a sound track lamp, a projector motor and a selector motor, 20 switch means for causing one of said motors to operate whenever either of said parallel switches is closed, means associated with said selector means for returning said coin counter one step 25 towards normal position and for moving said play counter one step away from normal position, a solenoid connected with each selector means, a pin adapted to be projected by each solenoid, a movable contact driven by said selector motor adapted to engage any projected 30 pin whereby said contact with said pin arrests the selector motor, means controlled by the engagement of said arm with any of said pins for returning said pin and for shifting said switching means for initiating the operation of the projector motor, and means controlled by the arrival 35 of the film at the end of its reproduction for returning the play counter one step towards initial 40 position.

JOHN F. EAKINS.
